DESIGN FOR A SLIPPER

Abraham Rosenberg, Norwalk, Conn., assignor to Rosenberg Brothers Slipper Company, Inc.,
South Norwalk, Conn., a corporation of Connecticut

Application February 12, 1938, Serial No. 75,101

Term of patent 3½ years

To all whom it may concern:

Be it known that I, Abraham Rosenberg, a citizen of the United States, residing at Norwalk, in the county of Fairfield and State of Connecticut, have invented a new, original, and ornamental Design for Slippers, of which the following is a specification, reference being had to the accompanying drawing, forming a part thereof, and in which:—

The characteristic features of my design reside in a slipper comprising a main body portion; a pair of narrow bands; an upper wide band adjacent said body portion and intermediate said narrow bands; an outer sole; and a lower wide band of substantially uniform width intermediate the sole and the body portion, and substantially evenly merging with said body portion.

I claim:

The ornamental design for a slipper, substantially as shown and described.

ABRAHAM ROSENBERG.
